UNITED STATES PATENT OFFICE.

EDWARD TODD, OF MADISON, NEW JERSEY.

SHOW BOX AND TRAY.

SPECIFICATION forming part of Letters Patent No. 292,875, dated February 5, 1884.

Application filed August 25, 1883. (No model.)

To all whom it may concern:

Be it known that I, EDWARD TODD, of Madison, Morris county, New Jersey, a citizen of the United States, doing business in New York, in the county of New York and State of New York, have invented certain new and useful Improvements in Show Boxes and Trays; and I do hereby declare the following to be a full, clear, and exact description of the invention, such as will enable others skilled in the art to which it appertains to make and use the same.

My invention relates to a combined packing-box and show-tray; and it consists, first, in the adaptation and application to a flat box of a rack-block, D, constructed in a novel manner, whereby the contained articles—such as gold pens with holders or similarly-constructed merchandise—are securely retained in place while being shipped, or while undergoing the handling in the store incidental to movement to and from the show-case or the safe; secondly, in the adaptation and application to the top of this rack-block D of a wood-veneer surface, whereupon is printed, painted, or otherwise portrayed the name or trade-mark of the maker or makers of the contained merchandise; thirdly, in the further adaptation and application to the top of this rack-block D of a strip of silicate, ground glass, porcelain, or other equivalent substance, and extending along the entire length of the block, whereupon the cost, price, and other marks of each article contained in the rack-block may be written with pencil or pen and removed therefrom with facility, when desired; fourthly, in the novel method of constructing the body of the tray, the body of the usually velvet-covered rest-block, and the main portion of the rack-block, all of wood, whereby the rest and rack blocks may be attached to the box by screws, and thereby become readily detachable, when necessary.

In the drawings, Figure 1 is a perspective view of my combined packing box and tray, showing in dotted lines the tapered end of a gold pen-holder clutched by the rack-block. Fig. 2 is an enlarged longitudinal section of the box and tray, showing one form of rack-block in transverse section, and located at an extreme end of the box. Fig. 3 is a similar

view, showing another form of rack-block located near the center of the box, a pen and holder, firmly held in place, being shown in dotted lines. Fig. 4 is an enlarged transverse view of the form of rack-block D shown in Fig. 3. Fig. 5 is a longitudinal section of that end of the box or tray in which is located the rack-block D, showing the latter attached to the end of the box and raised up from the bottom thereof; and Fig. 6 is a transverse section, cut through line x x of Fig. 2, of a portion of the box or tray, showing the rack-block D partly in front elevation and partly in section.

The combined box and tray especially referred to in this application and shown in the drawings is designed to contain gold pens and holders exclusively, the body A thereof, constructed of wood, containing at one end the usual rest-block, C, covered with velvet or similar soft material, and at or near the other end a rack-block, D. It has been the custom heretofore to fasten these blocks to the box or tray by means of glue. In order that these blocks may be readily removed and replaced by others after they have become worn or soiled, I attach them by screws d d.

By means of this improvement the body of the box can be saved for further use—a very important consideration for large shippers of gold pens and other similar articles of manufacture.

A card or other top, B, (shown in dotted lines in Fig. 2,) is used in connection with the wooden box-body.

Drilled at regular intervals in a horizontal transverse line through the rack-block D are holes a a. These holes are made larger in diameter than the tapering end of the pen-holder.

A rubber or other resilient strip, E, is securely seated in a groove sawed longitudinally into the rack-block D, and is provided with holes e e, smaller in diameter than the tapering ends of the pen-holders, and are constructed to register with holes a a in the rack-block D, as shown in Fig. 6. The tapering end of a pen-holder is inserted in one of the holes a in the rack-block D, and is forced through the hole e in the rubber strip E. The resilient edges of this hole clutch the pen-holder, thereby keeping it securely in place.

In order to further prevent the pen and holder from moving sidewise in the tray, an additional or supplemental rubber or other resilient strip, E', perforated in the same manner as strip E, but with still smaller holes, e' e', is seated in a groove cut parallel to and behind the groove cut for strip E, the holes e' e' also registering with holes a and e, as shown in Figs. 3 and 4.

10 It is obvious that the rack-block D may be attached to the bottom at the end, or near the center of the box, as shown in Figs. 2 and 3; or it may be raised up from contact with the bottom, and be attached to the end piece or 15 sides of the box without changing the character of my invention.

Attached to the top surface of the rack-block D is a wood-veneer or other polished strip, b, upon which is printed, painted, or 20 otherwise portrayed the firm name or trademark, or both, as shown in Fig. 1. A silicate, ground-glass, porcelain, or other equivalent strip, c, is also let in or otherwise attached to the top surface of the rack-block D. Upon 25 this strip is written with pencil or pen the mark of the goods, such mark being removed with facility, when desirable—an improvement heretofore greatly needed.

Having thus fully described my invention, 30 what I claim as new, and desire to secure by Letters Patent, is—

1. In a combined packing-box and show-tray, the rack-block D, constructed with holes a, in combination with rubber strip E, provided with holes e, as and for the purposes set forth.

2. In a combined packing-box and show-tray, the combination of the rack-block D, constructed with holes a, the strip E, provided with holes e, and the supplemental strip E', provided with holes e', the holes a, e, and e' registering with each other throughout the length of the rack-block, as and for the purposes set forth. 40

3. In a combined packing-box and show-tray, the rack-block D, constructed with holes a, and provided with perforated rubber strips E E', as hereinbefore described, in combination with the wood-veneer or other polished strip b, as and for the purposes set forth. 45

4. In a combined packing-box and show-tray, the rack-block D, constructed substantially as described, in combination with the silicate, ground-glass, or porcelain strip c, as and for the purposes set forth. 50

5. As a new article of manufacture, the wooden box and card or other top, in combination with the velvet or other covered wooden rest-block C, the wooden rack-block D, constructed substantially as described, and secured in place by the screws d d, whereby the blocks may be readily removed and others substituted, as set forth. 60

In testimony whereof I affix my signature in presence of two witnesses.

EDWARD TODD.
